UNITED STATES PATENT OFFICE.

JOHN R. MULLIN, OF ROME, NEW YORK, ASSIGNOR OF ONE-HALF TO JOHN F. HOLZINGER, OF ROME, NEW YORK.

NON-REFILLABLE BOTTLE.

1,172,034.

Specification of Letters Patent.

Patented Feb. 15, 1916.

Application filed June 30, 1915. Serial No. 37,243.

To all whom it may concern:

Be it known that I, JOHN R. MULLIN, a citizen of the United States, residing at Rome, in the county of Oneida and State of New York, have invented certain new and useful Improvements in Non-Refillable Bottles; and I do hereby declare the following to be a full, clear, and exact description of the invention, such as will enable others skilled in the art to which it appertains to make and use the same.

My invention relates to new and useful improvements in non-refillable bottles and my object is to provide a suitable permanent closure for the outer end of the neck of the bottle.

A further object is to provide ports in the closure through which the contents of the bottle will escape.

20 A further object is to provide means for permanently attaching the closure in the neck of the bottle. And a further object is to provide a suitable sealing mechanism below the closure.

25 Other objects and advantages will be hereinafter set forth and more particularly pointed out in the accompanying specification.

In the accompanying drawings which are 30 made a part of this application, Figure 1 is a vertical central sectional view through the upper end portion and neck of the bottle, showing my improved attachment applied thereto. Fig. 2 is a vertical central 35 sectional view through the closure for the upper end of the neck. Fig. 3 is a bottom plan view thereof, and Fig. 4 is a perspective view of a sealing cup for the neck of the bottle.

40 Referring to the drawings in which similar reference numerals designate corresponding parts throughout the several views, 1 indicates the body of the bottle and 2 the neck thereof, said neck being restricted at its lower end to form a seat 3, said neck gradually tapering outwardly from its lower to its upper end to provide a substantially conical-shape neck. The neck is provided, in its length, with an offset portion 4 45 to form a shoulder 5 on the interior of the neck upon which shoulder is seated the lower end of a closure block 6, the juncture of said shoulder with the lower end of the block forming a seal. The closure block 4 is provided at its upper end with a circumferen-

tial rib 7 which engages the upper end of the neck 2, and in order to permanently secure the block within the neck of the bottle, said block is provided adjacent its lower end with a circumferential groove 8 which registers with a similar groove 9 in the neck of the bottle, and in said grooves is seated any suitable form of resilient ring 10, preferably of cork, one half of the ring projecting into the groove 8 and the other half 65 into the ring 9 to form a substantially permanent lock for securing the block within the neck.

Extending centrally of the closure block 6 and from the upper end to a point adjacent the lower end thereof is an opening 11 communicating with the lower end of which is a plurality of ports 12, said ports being offset from the path of the opening 11 and extending through the remaining portion of 70 the closure block, the upper ends of each port being curved inwardly as shown at 13 so as to intersect the opening 11, thus leaving a solid portion 14 at the lower end of 75 the closure block to prevent the introduction 80 of a wire or other instrument for the purpose of manipulating the sealing mechanism in the lower portion of the neck.

Positioned within the neck 2 and below the closure block 6 is a flaring cup-shape 85 seal 15, the flare of the outer surface of the seal being coincident to the flare of the inner face of the neck so that when the bottle is sitting in a vertical position, the outer face of the seal will impinge against the inner face of the neck the full height of the seal to form a substantially liquid proof joint between the seal and neck.

The diameter of the seal is such that it will rest a distance below the closure block 95 when the bottle is in an upright position, thus permitting the seal to move longitudinally of the neck when the bottle is tilted and as said seal moves into the larger portion of the neck a passage will be formed 100 therearound, through which the contents of the bottle may escape when in a tilted position. To insure the free passage of the contents of the bottle between the upper end of the seal and the base of the closure block, 105 the upper end wall of the seal is scalloped or corrugated to provide lugs 16 which project outwardly and indentations 17 which project inwardly, thus when the seal engages the end of the closure block, the con- 110

tents of the bottle will pass through the indentations 17 and enter the ports 12.

In order to provide an additional seal for the neck of the bottle, a ball valve 18 is introduced into the neck and is of slightly greater diameter than the restricted portion of the neck so as to engage the seat 3, said valve having a weight 19 depending therefrom so as to normally hold the valve in engagement with the seat, the neck 20 connecting the weight to the ball valve being tapered from the weight to the valve so that when the bottle is tilted sidewise, the valve will move forwardly and release from the seat and in the forward movement strikes a socket 21 in the base of the seal 15, the force of the contact of the ball valve with the socket causing the seal to release from engagement with the neck of the bottle.

20 In assembling the various parts, the weight and the ball valve 18 are entered into the neck and permitted to descend therein until the valve engages the seat 3 at the restricted end of the neck, after 25 which the seal 15 is introduced into the neck and then the closure block 6 is placed into position. Previous to introducing the closure block into the neck, a ring 10 is entered in the groove 8 and compressed so that it 30 can be introduced into the neck of the bottle, the expansive action of the ring being such that as soon as the groove 8 is brought into registration with the groove 9, the outer edge of the ring will immediately expand 35 and enter the groove 9 thus permanently locking the block into the neck of the bottle with its lower end against the shoulder 5 and the rib at the outer end against the end of the neck.

40 It is understood, of course, that previous to assembling the various parts within the neck that the bottle has been filled with suitable liquid, and if desired, the ordinary form of cork 22 may be introduced into the 45 open end of the opening 11.

As all of the parts of this device are constructed of porcelain or glass, except the ring 10, they can be very cheaply constructed and readily applied to use within the

neck of the bottle. And it will also be seen that in view of the fact that the ports are out of line with the opening 11, thus leaving a solid portion of the material across the inner end of the opening, it will be impossible to introduce a wire or other instrument 55 to hold the seal arrangement in open position. It will likewise be seen that the contents of the bottle can not be removed until the bottle is tilted to an angle of substantially 45 degrees, and that as soon as the bottle is tilted from this position toward an upright position, the ball valve will immediately seat as will also the cup-shape seal, thereby preventing any of the liquid returning to the interior of the bottle. 60 65

Having thus fully described my invention what I claim as new and desire to secure by Letters Patent of the United States is:—

A non-refillable bottle, comprising a bottle having an outwardly flared neck, said neck in its length having an offset portion to form an interior shoulder, the restricted lower end of the neck forming a seat, a ball valve having an integral weight adapted to engage said seat, a hollow cup-shape seal having tapered walls to engage the tapered inner walls of the neck, the upper edge of said seal having spaced lugs to form passages, said seal also having a socket in its lower end, a closure having an opening extending partway therethrough, the lower portion of said closure having a plurality of ports offset from said opening and having their inner ends curved to intersect said opening, said closure and neck having registering grooves and a yielding ring adapted to interlock with said grooves and secure the closure within the neck and the lower end of the closure against the shoulder of the neck. 70 75 80 85 90 95

In testimony whereof I have signed my name to this specification in the presence of two subscribing witnesses.

JOHN R. MULLIN.
